REPEATING FIREARM

Harold F. Mossberg, New Haven, Conn., assignor
to O. F. Mossberg & Sons, Incorporated, New
Haven, Conn., a corporation of Connecticut

Application October 1, 1935, Serial No. 43,009

5 Claims. (Cl. 42—17)

This invention relates to improvements in repeating firearms, and more particularly to improvements in cartridge-elevating mechanism to successively bring the cartridges into proper position for insertion in the cartridge-chamber of a repeating firearm.

One object of this invention is to provide an improved, positive-acting cartridge-elevating mechanism for a repeating firearm.

10 Another object of this invention is to provide an improved positive-acting cartridge-elevating mechanism formed of simple elements readily manufactured and readily assembled to produce a durable efficient construction at minimum cost.

15 With the above and other objects in view, this invention includes all improvements over the prior art which are disclosed in this application.

In the accompanying drawings, in which one way of carrying out the invention is shown for 20 illustrative purposes:

20 Fig. 1 is a side elevation of the rear portion of a repeating firearm with the stock omitted and illustrating one embodiment of the present invention;

25 Fig. 2 is a bottom plan view of Fig. 1;

Fig. 3 is a longitudinal central vertical section of the construction shown in Fig. 1, with the parts in the positions they assume when the breech-bolt is in its fully-closed position, and 30 the firearm fired;

30 Fig. 4 is a view similar to Fig. 3, but showing the bolt at the start of its forward travel and the elevator about to effect the lifting of the cartridge;

35 Fig. 5 is a view similar to Fig. 3, but showing the bolt about midway of its forward travel and the cartridge in line with the cartridge-chamber;

Fig. 6 is a transverse vertical sectional view on line 6—6 of Fig. 3;

40 Fig. 7 is a transverse vertical sectional view on line 7—7 of Fig. 4;

Fig. 8 is a front elevation of the forward end of the breech-bolt removed;

Fig. 9 is a horizontal sectional view on line 45 9—9 of Fig. 8;

Fig. 10 is a perspective view of the bracket serving to hold the pivot of the cartridge-elevator lever;

Fig. 11 is a perspective view of the cartridge-50 elevator lever; and

Fig. 12 is a perspective view of the leaf-spring for acting on the cartridge-elevator lever.

In the description and claims, the various 55 parts are identified by specific names for convenience; but they are intended to be as generic

in their application as the prior art will permit.

Referring to the drawings, the barrel 10 has a cartridge-chamber 11 and the rear end of the barrel 10 is connected to the receiver 12. Longitudinally slidably in the receiver 12 is a breech-bolt 13 consisting of rear and forward parts 14 and 15 swiveled together in a well-known manner, with their line of separation indicated at 16. The bolt-handle 17 is rigidly secured to the rear part 14 of the breech-bolt, and the firing pin 18 is mounted to slide in the breech-bolt and to have its cocking-shoulder 19 engageable with the sear-shoulder 20 of the sear 21. The sear is actuatable by the trigger 22.

The forward part 15 of the breech-bolt at its extreme forward face 23 is provided with a 15 guide-and-retainer channel 24 (Fig. 8) formed by two spaced-apart undercut grooves 25 and 26 which form the lower part of the guide-and-retainer channel, and two spring-extractor fingers 27 and 28 which respectively provide upper 20 channel portions 29 and 30. The curved top-wall 31 may serve as a limit-shoulder to limit the upward travel of the rim of a cartridge. A tubular magazine 32 secured adjacent the forward end of the gun (not shown) extends rearwardly and is provided with the curved portion 33. Owing to the length of the tubular magazine 32, the portion 33 thereof is capable of being sprung down a sufficient distance to aid in feeding cartridges from the magazine in a manner 30 which is well known. A bracket 34 is secured to the receiver by screws 35, 36, and 37. The screw 37 extends through the hole 38 of the leaf-spring 39 and serves to hold the latter clamped 35 in place with the integral, bent, positioning-lug 40 thereof located between the opposite side-members 41 and 42 of the bracket 34. Pivoted to the bracket at 43 is a cartridge-elevator lever 44 having a projection 45. Integrally formed with the bracket 34 is an ejector 46 having an ejector-nose 47 adapted to travel in the slot 48 of the breech-bolt portion 15. The bracket 34 has the parts 41, 42, and 46 all formed as one integral member.

When the breech-bolt is in the closed position shown in Fig. 3, the lower surface 49 of the forward end of the breech-bolt presses the portion 50 of the tubular magazine 32 to spring the latter down somewhat, which permits the follower 51 which is pressed by a spring (not shown) to force the rim 52 of a cartridge 53 past the limit-shoulder 54, and as the breech-bolt moves rearwardly from its closed position shown in Fig. 3, the car- 55

tridge 53 is pushed rearwardly by the follower 51 and rocks around toward horizontal position.

As the surface 49 of the breech-bolt passes along the sloping surfaces 55 of the flexible tube 32, the latter is permitted to spring upwardly and force the rim 52 of the cartridge 53 up into the lower portion of the rim guide-and-retainer channel 24 and also close off passage of the next following cartridge, so that the latter will be stopped by the limit-shoulder 54. Continued movement of the breech-bolt to the rear now pulls the rim 52 and the cartridge 53 toward the rear to approximately the position shown in Fig. 4, at the same time extracting any fired shell by means of the extractor-fingers 27, 28 and ejecting it by the ejector-nose 47, that may have been in the cartridge-chamber. The cartridge 53 in its rearward movement engages the upper end 56 of the cartridge-elevator lever 44 and swings the latter rearwardly until the projection 45 passes to the right of the line of thrust of spring 39 through the pivot 43, whereupon the action of the spring 39 against the projection 45 swings the lever 44 downwardly to almost the position shown in Fig. 4. Further movement of the cartridge 53 rearward forces the lever fully to the position shown in Fig. 4 with the spring 39 pressing against the portion 57 and tending to swing the lever 44 upwardly and forwardly, and holding the same in engagement with the rim 52 and shell-body of the cartridge 53.

As the breech-bolt is moved forwardly toward the closed position, the rim 52 of the cartridge 53 presses against the rear edge of the portion 56 of the cartridge-elevator lever 44, thus compelling the lever 44 to swing upwardly and forwardly about its pivot 43, thus forcing the rim 52 of the cartridge 53 to slide upwardly in the rim guide-and-retainer channel 24 until the cartridge 53 is properly positioned, as shown in Fig. 5, for entry into the cartridge-chamber.

The above-described sequence of operations takes place repeatedly during the repeated firing and actuation of the breech-bolt of the firearm.

While the upturn-and-pullback type of repeating firearm has been used to illustrate the invention in the drawings, the invention can also be employed on other types of repeating firearms employing a breech-bolt, such as pump-action and automatic repeating firearms.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein.

I claim:

1. A repeating firearm including: a receiver; a barrel at the forward end of said receiver and having a cartridge-chamber; a breech-bolt having cartridge-guide-and-retainer means and movable in the receiver to closed and retracted positions; means for locating a cartridge below the axis of the cartridge-chamber and with its head adjacent the cartridge-guide-and-retainer means of said breech-bolt when the breech-bolt is in retracted position; and a cartridge-elevator lever pivoted below and forward of the head of such a positioned cartridge when the breech-bolt is in retracted position, with said lever extending upward and rearward from said pivot and in engagement with such a positioned cartridge, said

pivoted lever being so constructed as to be forced by direct positive engagement of the cartridge therewith, to swing the lever upward and forward and raise the cartridge along said cartridge-guide-and-retainer means into proper position for insertion in the cartridge-chamber when said breech-bolt is moved from retracted to closed position.

2. A repeating firearm including: a receiver; a barrel at the forward end of said receiver and having a cartridge-chamber; a breech-bolt having cartridge-guide-and-retainer means and movable in the receiver to closed and retracted positions; means for locating a cartridge below the axis of the cartridge-chamber and with its head adjacent the cartridge-guide-and-retainer means of said breech-bolt when the breech-bolt is in retracted position; a cartridge-elevator lever pivoted below and forward of the head of such a positioned cartridge when the breech-bolt is in retracted position, with said lever extending upward and rearward from said pivot and in engagement with such a positioned cartridge, said pivoted lever being so constructed as to be forced by direct positive engagement of the cartridge therewith, to swing the lever upward and forward and raise such a positioned cartridge along said cartridge-guide-and-retainer means into proper position for insertion in the cartridge-chamber when said breech-bolt is moved from retracted to closed position; and a spring to urge said lever upward and forward to engage such a positioned cartridge.

3. A repeating firearm including: a receiver; a barrel at the forward end of said receiver and having a cartridge-chamber; a breech-bolt having cartridge-guide-and-retainer means and movable in the receiver to closed and retracted positions; means for locating a cartridge below the axis of the cartridge-chamber and with its head adjacent the cartridge-guide-and-retainer means of said breech-bolt when the breech-bolt is in retracted position; and a cartridge-elevator lever pivoted below and forward of the head of such a positioned cartridge when the breech-bolt is in retracted position, with said lever extending upward and rearward from said pivot and in engagement with the rim and shell-body of such a positioned cartridge, said pivoted lever being so constructed as to be forced by direct positive engagement of the cartridge therewith, to swing the lever upward and forward and raise the cartridge along said cartridge-guide-and-retainer means into proper position for insertion in the cartridge-chamber when said breech-bolt is moved from retracted to closed position.

4. A repeating firearm including: a receiver; a barrel at the forward end of said receiver and having a cartridge-chamber; a breech-bolt having an upwardly-extending cartridge-guide-and-retainer channel and movable in the receiver to closed and retracted positions; means for locating a cartridge below the axis of the cartridge-chamber and with its head in the lower portion of said cartridge-guide-and-retainer channel when the breech-bolt is in retracted position; and a cartridge-elevator lever pivoted below and forward of the head of such a positioned cartridge when the breech-bolt is in retracted position, with said lever extending upward and rearward from said pivot and in engagement with such a positioned cartridge, said pivoted lever being so constructed as to be forced by direct positive engagement of the cartridge therewith, to swing the lever upward and forward and raise the car-

tridge along said channel into proper position for insertion in the cartridge-chamber when said breech-bolt is moved from retracted to closed position.

5. A repeating firearm including: a receiver; a barrel at the forward end of said receiver and having a cartridge-chamber; a breech-bolt having an upwardly extending cartridge-guide-and-retainer channel and movable in the receiver to closed and retracted positions; means for locating a cartridge below the axis of the cartridge-chamber and with its head in the lower portion of said cartridge-guide-and-retainer channel when the breech-bolt is in retracted position; and

a cartridge-elevator lever pivoted below and forward of the head of such a positioned cartridge when the breech-bolt is in retracted position, with said lever extending upward and rearward from said pivot and in engagement with the rim and shell-body of such a positioned cartridge, the part of said lever engaging the cartridge being shaped to be forced by direct engagement of the cartridge therewith, to swing the lever upward and forward and raise the cartridge along said channel into proper position for insertion in the cartridge-chamber when said breech-bolt is moved from retracted to closed position. 5 10
